MOVING STAIRWAY

James Dunlop, Park Ridge, Ill., assignor to Westinghouse Electric Elevator Company, Chicago, Ill., a corporation of Illinois

Application June 26, 1937, Serial No. 150,493

6 Claims. (Cl. 198—16)

My invention relates to moving stairways and more particularly to devices for ensuring the safe operation of such stairways.

In following the operation of moving stairways I have found that there is a definite risk involved in the operation of the stairway as it approaches the combplate because of the inability of immediately stopping the stairway when articles get caught along the sides of the steps as they approach the combplate, or because something has caused a step to rise as it is about to pass under the combplate. When an accident results from one of these causes, it occasions considerable damage which might be avoided if the stairways were stopped immediately upon their first faulty action.

Therefore, it is an object of my invention to provide a safety means which will cause a stairway to stop its operation immediately when anything becomes jammed between the combplate and the steps, particularly at the ends of the steps, and also when anything causes a step, as it approaches its combplate, to rise to such an extent that it will not pass under the combplate without crushing against it.

Another object is to provide a moving stairway safety device which shall be simple and economical to construct, operate and maintain in operation.

For a better understanding of the invention, reference may be had to the accompanying drawing, in which:

Figure 1 is a view, partly in side elevation and partly in section, of a portion of the upper landing of a moving stairway provided with a safety device constructed in accordance with my invention;

Fig. 2 is a top plan view of a large portion of the moving stairway upper landing shown in Fig. 1;

Fig. 3 is a view in cross section of a portion of the safety device and step tread shown in Figs. 1 and 2, and

Fig. 4 is a modification of the safety device illustrated in Fig. 1.

Referring more particularly to the drawing, I have illustrated the upper landing portion of a moving stairway as supported upon a suitable framework, a small portion of which is shown as a pair of I-beams 1 and 2, a vertical standard 3 and a strut 4. A track rail 5 is supported upon the standard 3 by means of suitable brackets 6 and secured to the strut 4 by rivets 7. A second track rail 9 is disposed about the first track rail 5 and is maintained in position by the standard 3.

A guard rail 10 is mounted upon the standard 3 above the track rail 9 in position to cooperate therewith. The track rails 5 and 9 comprise the upper track for the moving stairway. A pair of lower track rails 11 and 12 are attached to the vertical standard 3 by suitable brackets 13 to provide the lower track.

As shown, the moving stairway comprises an endless series of movable steps 15 which are disposed to move along the track rails 5 and 9 in accordance with the speed at which the stairway is to be operated. Each of the steps 15 comprises a step tread 17 disposed upon a frame comprising a pair of horizontal bars or joists 18 and 19 supported by suitable risers 20 and 21. The lower ends of the risers are suitably connected by end bars 22 (only one of which is shown) to constitute a frame for the step tread.

Each of the step treads 17 is provided with a plurality of suitable parallel cleats 23 disposed in alinement with the stairway and a sufficient distance apart to provide a plurality of grooves 24. The cleats should be of such dimensions and spaced such distances apart as to provide suitable supports for the feet of the passengers without permitting the heels of the passengers' shoes to enter the grooves.

The front portion of the step indicated by the riser 21 is supported by a pair of leading wheels 25 while the rear portion of the step is supported by a pair of trailing wheels 26. With the step in its upper or stairway position, the leading wheels 25 travel on the track rail 9 and the trailing wheels 26 travel on the track rails 5.

The leading wheels 25 are mounted upon an axle 27 which extends through a geared chain 28 at each side of the step. Each of the gear chains 28 is provided with a plurality of rollers 29 by means of which it is supported upon and driven by a suitable sprocket wheel 30. The sprocket 40 wheels are firmly mounted upon and driven by a suitable driving shaft 32. The rotation of the sprocket wheels causes the gear chains 28 to move in accordance with the direction of operation of the sprocket wheels thereby carrying the endless 45 series of steps 15 around in their operative position.

Inasmuch as the gear chains on the sprocket wheels support the leading wheels, they do not need to be supported by track rails as they follow 50 the gear chains around the sprocket wheels at the landings. However, the trailer wheels 11 are not connected directly to the gear chains. Therefore, track rail 5 is continued by a curved section 34 to extend around the axis of the sprocket wheels. 55

A curved guard rail 35 is disposed to guide the trailer wheels 26 along the curved track section 34.

An electric motor 39 is provided for driving the sprocket wheels, through a countershaft 39, a reduction gearing 40 and a driving chain 41. An electro-magnetically controlled spring-applied brake 42 is disposed on the motor shaft 32 for stopping the stairway and preventing its operation when the motor 38 is deenergized.

Although any suitable control circuit may be provided for the motor and the brake, I prefer to employ the control circuit illustrated and described in the patent of Edgar M. Bouton No. 15 2,088,460.

A comb plate 44 is provided at the upper end of the stairway adjacent to the position occupied by each step and it reaches its uppermost point in order to permit the passengers to easily 20 step on or off the stairway. The combplate 44 comprises a base 45 provided with a plurality of teeth 46 disposed to enter the grooves 24 between the cleats 23 of each step as it moves through its uppermost position and causes the feet of the passengers to be transferred from or to the steps 25 as the stairway operates in the up or the down direction. The combplate may be mounted upon the structural beams 1 and 2 in any suitable manner.

In order to stop the operation of the stairway when any obstruction on the tread of the step at the side of the stairway is likely to be jammed against the teeth of the combplate or when a step rises out of its normal running position to such an extent, as it approaches the combplate, that continued movement of the step will cause it to crash into the comb teeth, I have provided a pair of feeler fingers 50 and 51 for determining whether or not the steps are free of obstructions and are in alinement with the comb teeth.

The finger 50 is mounted on one end of the combplate by a pivot 52 with its rear portion 53 extending under a shoulder 54 formed on the combplate. The front end of the finger is provided with a feeler portion 55 which extends several inches beyond the front edge of the comb teeth 46 and alongside the point where the edges of the steps and the balustrade 56 meet. The height of the finger is about the same as that of the teeth 46 and, inasmuch as the rear portion of the finger extends under the shoulder 54 of the combplate, the feeler portion of the finger can be stepped upon by the passengers without moving it in any way. The rear portion of the finger is connected to a switch 57 having a pair of contact members 58 biased to a closed position by a spring 59. The switch may be mounted in any suitable manner, as upon the I-beam 1, and its contact members are so connected in the 60 control circuit 60 for the stairway motor and brake that the stairway will stop when the switch opens.

With this construction, if the step rises out of its normal running position as it approaches the combplate, or if it has an obstruction say like the sole of a boy's shoe caught in it, it will cause the feeler portion of the finger to rise and thereby move the rear portion of the finger downwardly, thus opening the switch 57, breaking the circuit 60, deenergizing the motor 38 and applying the brake 42 to stop the stairway.

Inasmuch as stairways of this character are provided with powerful brakes and their control systems are rapid in operation, the use of 75 the feeler finger 50 will cause the stairway to be

stopped immediately before the step reaches the point of the comb teeth when the step is jammed or out of position and thereby prevent damage to the stairway.

The finger 51 is mounted in the opposite end 5 of the combplate in the same manner as that described for the finger 50. The fingers are located at each side of the steps to ensure as great a degree of safety as possible.

It will be obvious that the feeler finger 50 or 10 51 may be mounted in any other manner in any other position where it will be operated to open its switch by the steps rising out of their normal running position. For instance, in Fig. 4, the finger 51a is constructed with a vertical shaft 62 15 slidably disposed in a block 63 mounted on a portion of the balustrade 56a. A switch 58a having its contact members connected in the control circuit 60 is disposed at the upper end of the shaft 62. With this arrangement, if a step, 20 raised slightly out of its normal running position, engages the finger 51a, it will move the shaft 62 and thereby open the switch 58a thus interrupting the control circuit 60 to effect the 25 stopping of the motor and the stairway.

By reason of the foregoing description, it will be seen that I have provided a simple and inexpensive means for enhancing the safe operation of moving stairways and that it is economical to construct, operate and maintain in operation.

Although I have illustrated and described only one specific embodiment of my invention, it is to be understood that many changes therein and modifications thereof may be made without departing from the spirit and scope thereof.

I claim as my invention:

1. In a moving stairway provided with steps having treads, the combination with a motive means for driving the steps and a combplate disposed at one end of the stairway, of a finger having a feeler portion, means for mounting the finger with its feeler portion normally extending over a portion of the tread of a step away from the combplate, whereby it will be moved upwardly out of its normal position by the step when the step is raised out of its normal running position, and means responsive to movement of the finger out of its normal position for rendering the motive means ineffective and stopping the operation of the steps.

2. In a moving stairway having steps provided with treads, the combination with a motor means for driving the steps and a combplate disposed at one end of the stairway, of a feeler finger, means for mounting the feeler finger adjacent to the combplate with the feeler portion of the finger extending beyond the teeth of the combplate into a normal position close to the tread of the step approaching the combplate and in 60 position to be engaged by and moved out of its normal position by a step raised out of its normal running position in approaching the combplate or by an obstruction on the step, and means responsive to the movement of the feeler finger 65 out of its normal position for rendering the motor means ineffective and for stopping the stairway steps.

3. In a moving stairway having steps provided with grooves in their treads, the combination 70 with means for driving said steps, a frame disposed at one end of the stairway, and a combplate mounted on said frame with the comb teeth disposed to enter the grooves in the treads of the steps as they pass to the combplate, of a 75

- feeler finger mounted on the combplate and extending in front of the teeth of the combplate and out of line with the normal line of approach of the steps to the combplate but in position to be engaged and moved by a step when that step rises above its normal running position in approaching the combplate, and a switch responsive to movement of the feeler finger out of its normal position for rendering said means ineffective and stopping the stairway.
4. A moving stairway having steps provided with grooves in their treads, means for driving the steps, a combplate disposed at one end of the stairway with its teeth disposed to enter the grooves in the treads of the steps as they pass under the combplate, a pair of feeler fingers, means for pivotally mounting one of the fingers at each side of the combplate in position to extend beyond the teeth of the combplate and to enter cooperating grooves in the treads of the steps as they approach the combplate but in position to be engaged and moved upwardly out of normal position by a step raised above its normal running position in approaching the combplate or by an article lodged on that portion of the step adjacent the finger, and switch means responsive to movement of either finger out of its normal position for rendering the driving means ineffective and stopping the stairway steps.
5. In a moving stairway having steps provided with grooved treads, motive means for driving the steps, a combplate mounted at one end of the stairway with its teeth disposed to enter

cooperating grooves in the step treads as they pass under the combplate and provided with shoulders, a pair of feeler fingers, means for pivotally mounting a finger upon each end of the combplate with its one end extending under a shoulder on the combplate and its other end extending forwardly beyond the teeth of the combplate in line with cooperating grooves in the steps whereby a step raised out of its normal running position will tilt the finger, and means responsive to a tilting action of either of the fingers for rendering the motor ineffective and stopping movement of the steps.

6. In a moving stairway having an endless series of steps, a combplate disposed at one end of the stairway, a motor for driving the steps under the combplate, a control circuit for the motor, a normally closed switch in the circuit, a feeler finger, means for pivotally mounting the finger adjacent to the combplate with the finger portion of the finger extending beyond the teeth of the combplate into a normal position close to the tread of the step approaching the combplate and in position to be engaged by and moved out of its normal position by a step raised out of its normal running position in approaching the combplate or by an obstruction on the step, and means connecting the rear portion of the finger to the switch whereby operation of the finger out of its normal position will open the switch to effect deenergization of the motor and stop the stairway.

JAMES DUNLOP.
